UNITED STATES PATENT OFFICE

2,330,264

SHOE MACHINE

Charles G. Brostrom, Lynn, Mass., assignor to
United Shoe Machinery Corporation, Flemington, N. J., a corporation of New Jersey

Application September 30, 1942, Serial No. 460,212

8 Claims. (Cl. 12—7)

This invention relates to shoe machines, and is herein illustrated as applied to a lasting machine constructed generally as disclosed in United States Letters Patent No. 2,238,244, granted on April 15, 1941, on an application of mine. It is to be understood, however, that the invention is not limited to the embodiment herein shown.

The machine shown in the above-mentioned Letters Patent, which is particularly intended for use in lasting with cement the opposite sides of the ball portions of shoes, is provided with a rotary lasting device of generally circular form which rotates completely about its axis in each lasting operation, the device including a gripper for gripping and applying a pull to the upper and means for wiping the margin of the upper inwardly over the insole. Included also in this lasting device is a shoe-controlling member arranged to engage the insole near the edge of the latter and to move the last heightwise relatively to the gripper to cause the gripper to pull the upper, this member thereafter being moved inwardly over the insole in frictional contact therewith by the rotation of the device. It has been found that under some conditions lasting cement, especially latex, adhering to the insole-engaging face of this member may cause the latter to distort or displace a portion of the insole in moving inwardly over it. In operating, for example, on a shoe of that type in which the central portion of the forepart of the insole is removed and the opening covered by a thin patch, the member in its inward movement over the insole may displace the patch and may distort also the marginal portion of the insole.

To guard against such objectionable results the present invention provides means for applying moisture to the insole-engaging face of the above-mentioned member. It has been found that moisture, especially water, so applied counteracts in a sufficiently effective manner such tendency as there may be for the insole to adhere to the member. For the purpose in view the construction herein shown comprises a moisture-applying pad, cam-controlled means for moving the pad into contact with the insole-engaging face of the member at a predetermined time in the rotation of the lasting device, and means for supplying moisture to the pad from a water-containing receptacle.

The invention will now be more particularly described with reference to the accompanying drawings and thereafter pointed out in the claims.

In the drawings,

Fig. 1 is a view in right-hand side elevation of

the upper portion of a machine constructed as shown in the above-mentioned Letters Patent with the present invention applied thereto;

Figs. 2, 3, 4 and 5 are fragmentary views, partly in right-hand side elevation and partly in section, showing portions of the lasting device in different positions which they assume in the course of the lasting operation;

Fig. 6 is a view similar to the upper portion of Fig. 1, but showing the parts in different positions than in Fig. 1; and

Fig. 7 is a perspective view of a shoe after it has been operated upon by the machine.

In view of the disclosure in the above-mentioned Letters Patent, only such parts of the machine as it is necessary to refer to for an understanding of the invention will be herein briefly described. The machine is provided with a rotary lasting device 2 including a segmental member 4 fast on a rotatable shaft 6. The member 4 has a peripheral rim 8 concentric with the shaft 6 and extending considerably more than half way around the shaft. Between the two ends of the rim is a recess in which is located, as part of the rotary lasting device, a gripper 10 for gripping the margin of the ball portion of the upper at one side of a shoe supported at its other side on a shoe rest 12 and under control of the operator. The gripper comprises a jaw 14 and three jaws 16 opposed to the jaw 14, as more fully disclosed in the above-mentioned Letters Patent, only two of the jaws 16 being visible in the drawings. The jaw 14 is moved by the operator into position to grip the margin of the upper against the jaws 16, as illustrated in Fig. 2, by downward movement of a member 18. At this time the insole a of the shoe is engaged near its marginal edge by a plate 20 supported by one of the jaws 16. After the gripping of the margin of the upper the starting of the power operation of the machine takes place, whereupon the plate 20 is moved forward automatically, as illustrated in Fig. 3, and thereby moves the last and shoe heightwise relatively to the gripper to cause the gripper to pull the upper. As the upper is thus pulled, the gripper 10 remains stationary, but the segmental member 4 begins its rotary movement and carries a wiper 22 on the rim 8 to a position substantially contiguous to the margin of the upper, as also illustrated in Fig. 3. The gripper 10 is then forced, by the action of the rim 8 on the jaw 14, to rotate with the segmental member 4. As the gripper thus starts to rotate it exerts an inward pull on the margin of the upper, followed immediately by return movement of the plate 20

50

and release of the upper by the gripper, as illustrated in Fig. 4. Further rotation of the lasting device 2 as a whole causes the wiper 22, acting as an overlaying member, to wipe the margin of the upper inwardly over the insole into position to be secured thereto by cement previously applied to the shoe, the rim 8 thereafter exerting a still more forcible wiping action on the upper through corrugations 24 on its periphery (Fig. 5). For a better understanding of the construction thus far described the previously mentioned Letters Patent may be consulted.

It will be evident that as the gripper 10 moves inwardly over the insole in the course of the rotation of the lasting device the plate 20 moves with it in frictional contact with the bottom face of the insole. The shoe herein shown is one of a type having an insole from which the central portion of the forepart has been removed, the opening thus formed being covered by a comparatively thin patch b (Fig. 7) cemented to adjacent portions of the insole. It has been found that in operating on a shoe of this kind lasting cement, such as latex, which may be deposited on the insole-engaging face of the plate 20 upon contact of the insole therewith, may cause the plate to exert such a drag on the insole in moving inwardly over it as to displace the thin patch b and perhaps also the marginal portion of the insole. To guard against such an occurrence, the machine herein shown is provided with means for moistening with water the insole-engaging face of the plate, experience having proved that this lessens in a sufficiently effective manner any tendency for an insole to adhere to the plate. For the purpose in view a pad 26, which may be of felt, is mounted over the rotary lasting device 2 on an arm 28 which is fast on a rockshaft 30 supported by a bracket 32 on the head of the machine, and also fast on this rockshaft is an arm 34 having a roll 36 engaged by a cam 38 on the shaft 6. A spring 40 connected to the arm 34 tends to swing this arm and the arm 28 downwardly and thus holds the roll 36 at all times against the cam 38.

Formed in the cam is a recess 42 which arrives in position to receive the roll 36 when the rotary lasting device 2 arrives in such a position that the insole-engaging plate 20 is directly under the pad 26 (Fig. 6). The pad is therefore moved downwardly into contact with the plate to moisten the plate, the pad being maintained in a moistened condition by a wick 44 leading therefrom to a water receptacle 46 supported on the head of the machine. Moisture is thus applied to the plate 20 near the end of the rotary movement of the lasting device 2 to prepare the plate for use in the next operation of the machine on a shoe. It will be understood that if the machine should remain idle long enough for the moisture on the plate to evaporate, the latter may be moistened again by causing the machine to operate idly before its next operation on a shoe. It will also be understood that at all times except when the plate 20 is under the pad 26 the pad is maintained by the cam 38 out of engagement with the rotary lasting device.

Having described the invention, what I claim as new and desire to secure by Letters Patent of the United States is:

1. In a shoe machine, the combination with means for operating on a shoe including an insole mounted on a last, of a shoe-controlling member arranged to engage the bottom face of

the insole, means for effecting relative movement of said member and the shoe to cause the member to traverse said face in frictional contact therewith, and means for applying moisture to said member to lessen any tendency for the insole to adhere thereto.

2. In a lasting machine, a member movable in frictional contact with the bottom face of an insole on a last in the lasting operation, and means for applying moisture to said member to lessen any tendency for the insole to adhere thereto.

3. In a lasting machine, the combination with means for laying the margin of an upper inwardly over an insole on a last, of a shoe-controlling member arranged to engage the bottom face of the insole and movable inwardly over said face in frictional contact therewith to make way for said overlaying means, and automatic means for applying moisture to said member to lessen any tendency for the insole to adhere thereto.

4. In a lasting machine, a rotary lasting device including a member arranged to engage the bottom face of an insole on a last and movable along said face in frictional contact therewith in response to rotation of the device, and automatic means for applying moisture to the insole-engaging face of said member at a predetermined time in the rotation of the device.

5. In a lasting machine, a rotary lasting device including a member arranged to engage the bottom face of an insole on a last and movable along said face in frictional contact therewith in response to rotation of the device, a pad movable into and out of position to apply moisture to the insole-engaging face of said member, automatic means for moving the pad into that position at a predetermined time in the rotation of the device, and means for supplying moisture to the pad.

6. In a lasting machine, a rotary lasting device including a member arranged to engage the bottom face of an insole on a last and movable along said face in frictional contact therewith in response to rotation of the device, a pad arranged to apply moisture to the insole-engaging face of said member, a water-containing receptacle, and a wick leading from said receptacle to the pad for conducting water to the pad.

7. In a lasting machine, a rotary lasting device including a member movable to lay the margin of an upper inwardly over an insole on a last and including also a shoe-controlling member arranged to engage the bottom face of the insole and movable inwardly over said face as the device is rotated, a pad for applying moisture to said shoe-controlling member, an arm supporting said pad and movable to carry the pad into moisture-applying position, and means for thus moving said arm at a predetermined time in the rotation of the device.

8. In a lasting machine, a rotary lasting device including a member movable to lay the margin of an upper inwardly over an insole on a last and including also a shoe-controlling member arranged to engage the bottom face of the insole and movable inwardly over said face as the device is rotated, a pad for applying moisture to said shoe-controlling member, a movable support for said pad, a cam for controlling said support, and a spring for moving the support to carry the pad into moisture-applying position when permitted by the cam.
